B. G. FOSTER

BIRD HOUSE

Filed Sept. 2, 1922

Fig. 1.

Fig. 2.

Inventor

Bertram G. Foster

UNITED STATES PATENT OFFICE.

BERTRAM G. FOSTER, OF WASHINGTON, DISTRICT OF COLUMBIA.

BIRD HOUSE.

Application filed September 2, 1922. Serial No. 585,943.

To all whom it may concern:

Be it known that I, BERTRAM G. FOSTER, a citizen of the United States, residing at Washington, District of Columbia, have invented certain new and useful Improvements in Bird Houses, of which the following is a specification.

As is well known to those having a knowledge of the habits of wild birds, some do not need landing perches or platforms outside the entrance and exit openings of the houses, and where such are provided other birds are apt to alight thereon and dispute ownership. On the other hand with other birds it is desirable that alighting supports be provided. It is one of the objects of the present invention to provide a structure that may be reversed and thereby a landing platform provided or eliminated, as desired, the element constituting such platform in one case constituting an overhanging roof or eaves when the house is reversed. Another and very important object is to provide a very simple and practical structure that can be cheaply manufactured, comprises parts readily obtainable and easily assembled, and which can be quickly dismembered for cleaning and as quickly reassembled.

30 In the accompanying drawings:

Figure 1 is a perspective view of the preferred embodiment of the invention when arranged for birds not requiring an alighting support,

35 Figure 2 is a perspective view showing the house reversed and providing a landing platform,

Figure 3 is a longitudinal sectional view.

40 Figure 4 is a detail perspective view of the retaining spring.

In the embodiment disclosed a hollow body is employed of generally spherical shape and truncated. Preferably it is a single piece and a cocoanut shell can be conveniently employed. The body is designated 5, and is provided in one side with an entrance and exit opening 6. The truncated end is formed by cutting off one end, forming an opening 7 and providing a flat circular bearing edge 8.

45 A closure plate 9 extends over the opening 7 and rests against the edge 8. The body is secured to this plate, preferably by

means of a cross bar 10 bridging the opening and having its ends bearing against the inner faces of the convergent walls of the body. This cross bar is preferably of spring metal, and passing through the central portion thereof is a clamping bolt 11 that passes through the plate 9 and has a knob nut 12 threaded on its outer end. The bar 10 is preferably a leaf-spring normally flat, and therefore when the bolt is drawn tight this bar will be bowed, insuring a tight clamping action and conforming to the individual contour of the body. The plate 9 is secured at its rear end to a right angularly disposed bracket plate 13 which extends behind the body and preferably is abutted against by said body. This plate may have suitable openings for the reception of screws 14, by means of which the device can be secured to a tree, pillar, wall or other support.

50 With this construction if the house is to be used for birds that do not need a landing platform, the bracket is secured with the closure plate uppermost as shown in Figure 1. When so arranged the plate 9 extends over the body and constitutes a roof therefor. When a landing platform is desired the structure is mounted in reversed relation or as shown in Figure 2. Inasmuch as the front end of the closure plate projects beyond the body, it will be noted that the projecting portion constitutes a platform on which the birds may alight. Obviously the body can be quickly affixed to and detached from the support, and when detached the interior can be readily cleansed. Another advantage for the structure disclosed is that it permits the body to be turned with the bolt 11 as an axis, so that the entrance and exit opening 6 can be differently positioned with respect to the bracket. The plates 9, and 13 may be duplicates and thus cheaply constructed in quantities. Moreover when the body is in underhung or depending relation its bearing against the fastening or bracket plate 13 serves to brace it and the supporting plate 9.

55 From the foregoing, it is thought that the construction, operation and many advantages of the herein described invention will be apparent to those skilled in the art, without further description and it will be

understood that various changes in the size, shape, proportion and minor details of construction, may be resorted to without departing from the spirit or sacrificing any 5 of the advantages of the invention.

Having thus fully described my invention, what I claim as new, and desire to secure by Letters Patent, is:

1. A bird house comprising a hollow body 10 having an opening in one end and an entrance and exit opening in one side, the walls converging to the end opening, a closure for the end opening, retaining means for the closure bearing against the inner 15 faces of the converging walls, and an adjustable connection between the closure and retaining means for clamping the closure firmly and fixedly to the body.
2. A bird house comprising a hollow body 20 having an opening in one end, and an entrance and exit opening in one side, the walls converging to the end opening, a closure for the end opening, a retaining device in the body bridging the end opening and resting 25 against the inner faces of the converging walls, and a detachable connection between the device and closure for clamping the latter fixedly to the body.
3. A bird house comprising a hollow body 30 having an opening in one end, and an entrance and exit opening in one side, the walls converging to the end opening, a closure for the end opening, a bendable retaining strip in the body bridging the end opening and 35 resting against the inner faces of the converging walls, and a detachable connection between the device and closure for drawing the two towards each other and clamping the closure firmly to the body.
4. A bird house comprising a hollow body 40 having an opening in one end and an entrance and exit opening in one side, the walls converging to the end opening, a closure for the end opening, retaining means 45 for the closure connected thereto through the opening and bearing against the inner faces of the converging walls, and means for mounting the closure on a support said closure thereby constituting holding means 50 for the body.
5. A bird house comprising a hollow body 55 having an opening in one end and an entrance and exit opening in one side, the walls converging to the end opening, a closure for the end opening, retaining means for the closure connected thereto through the opening and bearing against the inner 60 faces of the converging walls, and a bracket piece secured to the rear side of the closure and constituting means for mounting the house on a support.
6. A bird house comprising a hollow body 65 having an opening in one end and an entrance and exit opening in one side, the walls converging to the end opening, a clo-

sure for the end opening, retaining means for the closure connected thereto through the opening and bearing against the inner faces of the converging walls, and a bracket piece secured to the rear side 70 of the closure and constituting means for mounting the house on a support, said body having a bearing against the bracket piece.

7. A bird house comprising a hollow body 75 having an entrance and exit opening in one side, a plate secured to one end of the body and projecting beyond the side having the opening, and means for mounting the plate on a support in either of reversed positions 80 whereby said plate will either constitute a roof for the body and the latter will underhang the same or the projecting portion will constitute a platform beneath the entrance and exit opening.

8. A bird house comprising a hollow body having an entrance and exit opening in one side, a plate secured to one end of the body and projecting beyond the side having the opening, and a bracket plate secured to the rear end of said first plate and extending alongside the rear of the body, said structure being reversible whereby said first plate will either constitute a roof for the body and the latter will underhang the same or the projecting portion will constitute a platform beneath the entrance and exit opening.

9. A bird house comprising a single piece truncated generally spherical body having its truncated end open and also having an entrance and exit doorway in one side, a closure detachably secured to the body over the truncated open end and means connected to the closure for supporting the body.

10. A bird house comprising a single piece truncated generally spherical body having its truncated end open and also having an entrance and exit doorway in one side, a closure plate extending across the truncated end, means connected to said plate, extending through the opening and overlapping the adjacent walls for securing the plate in place, and means connected to the plate for mounting the same and the body on a support.

11. A bird house comprising a cocoanut shell having an entrance and exit opening in one side and having one end portion cut away to provide an end opening, and a closure fixedly secured across said opening and extending outwardly beyond the shell to form a platform.

12. A bird house comprising a hollow body having an opening in one end and an entrance and exit opening in one side, a support and closure for the end opening extending across the same, and means in the opening for fixing the body to the support and closure and permitting the body to be rotated with respect to the support to differently 130

position the entrance and exit opening with relation to said support.

13. A bird house body comprising a cocoanut shell having an entrance and exit opening in one side and having one end cut away to provide an end opening, a support for the body including a closure and supporting plate extending across the end opening, and a clamping device engaging the inner side

of the shell and engaged with the plate 10 through the opening, said device permitting the shell to be differently positioned on the plate with the entrance and exit opening in different relations with respect to the support. 15

In testimony whereof, I affix my signature.

BERTRAM G. FOSTER.
